SOUND-ABSORBING TILE OR THE LIKE

Charles W. Allen, Jr., Chicago, Ill., assignor to United States Gypsum Company, Chicago, Ill., a corporation of Illinois

Filed Apr. 19, 1963, Ser. No. 74,538

Term of patent 14 years

(Cl. D18—2)

Fig. 1

Fig. 2

Fig. 3

FIG. 1 is a top plan view of a sound-absorbing tile or the like showing my design;

FIG. 2 is an edge view of said sound-absorbing tile or the like; and

FIG. 3 is a partial sectional view taken along the line 3—3 of FIG. 1.

I claim:

The ornamental design for a sound-absorbing tile or the like, substantially as shown.
